MASSAGE TABLE

Roann Golden, Oakland, Calif.

Application November 22, 1946, Serial No. 711,602

8 Claims. (Cl. 128—24.3)

1.

This invention relates to improvements in methods and means for reducing and distributing excess fat through combination massage and heat treatments, and relates particularly to a new and improved type of temperature control cabinet and massage machine, and which cabinet and machine is at all times under immediate and direct control of the operator.

The cabinet includes a vaporizer which may be supplied with water or other vaporizable material, and also includes separate heating means so that the interior of the cabinet may be adjusted or maintained at any desired temperature, and also a bed which has fixed sections and movable rolling sections with the rolling sections individually controllable so that massaging is under control for the different parts of the body.

The person is treated in a reclined position, with the head and face outside of the cabinet. The treatment may include both sweat bath and massage, or either of these alone.

The objects and advantages of the invention are as follows:

First, to provide in a single unit a combination sweat bath cabinet and massaging machine.

Second, to provide a unit as outlined in which the temperature can be controlled for any desired treatment or to suit the person being treated.

Third, to provide a unit as outlined in which water or medicinal vapors can be developed to envelope the body of the person being treated.

Fourth, to provide a unit as outlined with a bed consisting of fixed body supporting sections, and with the massaging support sections controllable at will for idling or for massaging.

Fifth, to provide a unit as outlined with a hood which extends the full length of the unit and which is openable to permit complete and unrestricted access to the interior and so that a person can lie directly on the bed without passing through any restrictive passageways.

In describing the invention reference will be made to the accompanying drawings, in which:

Figure 1 is a longitudinal sectional elevation through the invention.

Figure 2 is a plan view of the invention with the hood removed.

Figure 3 is a transverse sectional elevation through the invention.

Figure 4 is an end view of the invention showing the hood in raised position.

Figure 5 is an enlarged fragmentary sectional elevation showing one of the massage roller clutches and its external manual control.

Figure 6 is an enlarged fragmentary sectional view showing the massage roller mounting.

Figure 7 is another fragmentary sectional view showing one of the roller sections in an end view.

The invention consists of a cabinet comprising a base portion 10, including a front wall 11, rear

2.

wall 12, head-end wall 13, foot end wall 14, and a bottom wall 15, and suitably supported on legs 16, which are provided with casters 17, and a hood portion 18, including a semi-cylindrical cover wall 19, which is fully closed at the foot end by a wall 20, and having a wall 21, at the head end provided with an opening 22.

The bed consists of a series of spaced fixed supports 23, to 26, with a pad 27, formed on the support 26, functioning as a foot rest, and adjustable support 28, is padded as indicated at 29, and is hinged to the head-end wall as indicated at 30, and functions as a head rest and is inclinably adjustable by means of the strut 31, which is adjustable in a series of notches 32. The supports 23, to 25, may also be padded if desired.

Mounted within the lower portion of the cabinet is a plurality of spaced heating units 33, and 34, each of which is hooded as indicated at 35, and being indicated as electrical with leads 36, for connection to suitable control switches and a source of power, such connections and switches being well known in the art and therefore not being shown. A suitable guard 37, is located beneath each heating unit.

Mounted in heat exchange relation with at least one of the heating units is a receptacle 38 which may be filled with water or other vaporizable material.

30. Mounted in each of the spaces between the fixed supports 23, to 26, is a roller assembly consisting each of a carrier or vehicular frame 39, in which a series of rollers 40, are rotatably supported as indicated at 41, these carriers being supported in tracks 42, on rollers 43, and each of these carriers includes a cross member 44, having a depending bracket 45, centrally located and formed as a yoke carrying a roller 46, at its lower end and with a cross member 47, in spaced relation above the roller to form a passage for the reciprocating bar 48. The rollers 43, for each roller section are connected together by the side bars 49.

The reciprocating bar 48, is driven through a connecting rod 50, pivoted at one end to the reciprocating bar 48 at 51, and having its other end driven by a crank 52, which in turn is driven through a speed reducer 53, by a motor 54.

The clutch mechanism for the roller sections is shown in its simplest form as consisting of a series of apertures 55, formed for each roller section in the reciprocating bar, and a pin 56, to engage in any one of the apertures of a series, this pin continuing into a threaded portion 57, which operates in a threaded passage in the depending bracket 45.

A knob 58, projects from the front of the cabinet for each roller section and has a shaft 59 which is rotatably mounted in the front wall of the cabinet 60, as indicated at 60, and a telescopic shaft 61,

connects between the screw 57 and the shaft 59, through universal joints 62 and 63.

In operation the hood is opened as indicated in Figure 4, and the person to be treated lies on the bed with the head resting on the support 29, and the feet resting on the support 27.

For a plain steam bath or other type of vapor bath, the material to be vaporized is placed in the receptacle 38, the heating units are energized, and the cover closed down over the person, all pins 56, having been retracted by turning the knobs 53. The roller sections are therefore idle and will move with movements of the body. The temperature is controlled by well known means.

If there is to be only a massage treatment without any heat treatment, the roller sections are adjusted to the proper positions to massage the portions of the body requiring massage and the knobs are then turned to cause the pins 56, to engage in the closest apertures 55, after which the motor 54, is cut in circuit which causes the roller sections to reciprocate relatively slowly rolling back and forth under the body with the body supported thereon. When the person is lying face down, obviously no massaging of the shins and possibly no massaging of the breasts is desired, therefore only the central roller section will be engaged the others remaining idle. The apertures 55, permit the roller sections to be adjusted suitably for persons of different heights and assure proper massage of the exact areas of the body desired. When heat or vapor is not desired, the hood may be left open or may be closed.

At any time when massaging of any specific area is to be discontinued, it is merely necessary to retract the pin by turning the knob on the front of the cabinet, the telescopic shaft and universal joints permitting engagement or disengagement of the clutch at any time.

Obviously heat or vapor treatments and massaging can be simultaneously applied, for which reason the machine is adaptable to any desired single treatment or combination of simultaneous treatments or series of treatments, including dry heat, steam bath, vapor bath, and massage.

The rollers are formed preferably of a relatively soft or resilient material such as live rubber and their top surfaces are in a plane with the top surfaces of the fixed supports.

I claim:

1. A massage cabinet, in combination; a cabinet having a bed portion consisting of spaced fixed supports and intervening roller sections and driving means for reciprocating said roller sections in a direction lengthwise of the bed portion and means manually controllable for freeing any of said roller sections from said driving means at will, and a hood for enclosing said bed portion.

2. A structure as defined in claim 1; said cabinet comprising a box-like structure having said bed portion mounted at the top thereof, and said intervening roller sections consisting each of a frame carrying a plurality of spaced rollers on axes at right angles to the longitudinal axis of the bed portion; said box-like structure having a track along each side interiorly, and a plurality of rollers linked together, for each track with the frames riding on the rollers.

3. A structure as defined in claim 1; said intervening roller sections each consisting of a frame with rollers spacedly supported therein transversely to the longitudinal axis of the bed, with

the frame movably supported at both ends; said driving means comprising a bar supported lengthwise of said cabinet and means for reciprocating said bar, and clutch means for each frame and manually controllable from the front of the cabinet for engagement or disengagement between the frame and the bar at will, and means for adjusting the relative position of the frame on the bar for reciprocation through a defined area, at will.

4. A structure as defined in claim 1; said cabinet comprising a box-like structure having said bed portion mounted at the top thereof, and said intervening roller sections consisting each of a frame carrying a plurality of spaced rollers on axes at right angles to the longitudinal axis of the bed portion; said box-like structure having a track along each side interiorly, and a plurality of rollers linked together, for each track with the frames riding on the rollers; heating means for heating the interior of said cabinet, and a receptacle located in heat transfer relation to said heating means for production of vapors within said cabinet.

15 5. In combination, a support forming an enclosure and a bed mounted at the upper end of said support and comprising spaced cross members in fixed position and intervening roller sections having rollers with the topmost surfaces in the plane of the cross-members, said roller sections being mounted for reciprocation in a direction lengthwise of the bed; driving means for reciprocating said roller sections; and adjustable clutch means manually controllable from the front of the support for causing engagement or disengagement between any roller section and said driving means at will and for establishing the relative area through which a roller section operates to compensate, for relative locations to be massaged.

6. A combined sweat and massage cabinet comprising; a support formed as a box-like structure to form an enclosure and having front and back walls and a head end wall; a track mounted on the inside of each said front and said back wall adjacent the top; a cross member at each end and fixedly mounted at the top of the support, and cross-members spacedly fixedly mounted therebetween; a vehicular frame for each space and supported on said tracks in the spaces between the cross-members; driving means for reciprocating said frames and individual clutching means therefor and means for manually controlling said clutching means at will from the front of the cabinet; each of said frames having a plurality of spaced rollers rotatably supported therein with the tops of the roller bearings in the same plane as the top surfaces of the cross-members.

60 7. A structure as defined in claim 6; a head support mounted on the head end wall exteriorly of the support and means for adjusting said head support as to angularity, and a hood hingedly mounted on the back wall to close over the bed and having a head end wall provided with a passage in registry with the head supports.

8. A structure as defined in claim 6; a head support mounted on the head end wall exteriorly of the support and means for adjusting said head support as to angularity, and a hood hingedly mounted on the back wall to close over the bed and having a head end wall provided with a passage in registry with the head support; heating units mounted within said enclosure beneath said bed, and a receptacle mounted in heat exchange

relation to said units for creating vapor within
said enclosure.
